UNITED STATES PATENT OFFICE.

CARL SEGNA, OF NEW YORK, N. Y.

DESIGN FOR A SPEED-WAGON BODY.

SPECIFICATION forming part of Design No. 34,041, dated February 5, 1901.

Application filed January 15, 1901. Serial No. 43,426. Term of patent 3½ years.

To all whom it may concern:

Be it known I, CARL SEGNA, a citizen of the United States, residing at New York, (Brooklyn,) in the county of Kings and State of New York, have invented and produced a new and original Design for Speed-Wagon Bodies, of which the following is a specification, reference being had to the accompanying drawing, forming a part hereof.

10 The figure is a perspective view of a speed-wagon body, showing my new design.

The structure of the body is composed of cylindrical tubing. The base-piece 1 of the structure is rectangular in shape, and from 15 said base-piece, at right angles thereto, extend uprights 2.

3 is the top front portion of the body, secured to the upper extremities of the uprights 2 at the front and sides and having curved 20 portions 4 arranged to extend to and engaging with the front of a seat 5.

6 is the rear portion of the top of the body,

also connected to the uprights 2, with the exception of the curved portions 7, which engage with the rear of the seat 5.

8 represents curved brace-pieces passing from the base 1 beneath the seat 5, with which they engage.

10 is a bent and curved tube forming the arms and back of the seat, being connected therewith by uprights 11, the front curved portions of the tube 10, (designated as 12,) being carried down to the seat 5.

Having described my invention, what I claim as new, and desire to secure by Letters 35 Patent, is—

The design for a speed-wagon body, as herein shown and described.

Signed by me at Brooklyn, New York, this 12th day of January, 1901.

CARL SEGNA.
